UNITED STATES PATENT OFFICE

WILLIAM L. TAYLOR, OF CINCINNATI, OHIO

PAPER BAG MACHINE

Application filed August 3, 1928. Serial No. 297,336.

This invention relates to paper bag machines and more particularly to the cutting unit thereof.

Heretofore in paper bag machines of the class used for making paper tobacco bags, composed of two thicknesses of paper, namely: a cover and a liner, it has been the common practice to use two cutting units for the reason that the liner is of a different width than the cover, one cutting unit being adjusted to cut the liner and the second cutting unit adapted to cut the cover.

The principal object of this invention is to eliminate one cutting unit, thereby reducing the initial cost of the equipment and the added adjustments needed in its operation.

Another object of this invention is that by eliminating one cutting unit I am enabled to re-locate the scoring mechanism of the machine, so that the scoring operation is accomplished before the printing operation, whereas with machines having two cutting mechanisms the scoring operation is accomplished after the printing operation. When the scoring operation succeeds the printing operation, and owing to the established location of the print on the bags, it is necessary to score through a wet print, smudging it to a very considerable extent, and making the bag unsightly.

With my improved single cutting mechanism I now cut out with one dieing out unit, which means that both of the webs of paper, namely: the liner and cover, are died out or cut out at one and the same time, which is of very considerable advantage in bag structure, as with two cutting out mechanisms, operating at two different points on the machine and then joining up the two plies or webs of paper afterwards, registry, which is necessary, is not always obtained, and in gluing the bags together the narrow ply, where bags are not properly registered, often overlaps the outer ply at the point of the glue flaps, so that perfect sealing is not had. This allows the liner to push down in the bag in the packaging operation in the plant of the tobacco manufacturer and where the bag is imperfectly

glued it is likely to burst open in the hands of the consumer. That is, not being perfectly alined and glued in accordance with the design of the bag, it is not efficient in production, and is not as serviceable in the hands of the consumer.

My invention consists in providing a pair of shoes horizontally arranged between the dieing out cylinders, which shoes are adapted to compensate for the difference in width of the respective plies or webs of paper, so that both webs may be died out at the same time and by one cutting unit.

My invention further consists in the construction, combination, location and arrangement of parts, as hereinafter more fully set forth and claimed.

In the drawings:

Fig. 1 represents a front elevation of a single cutting unit for a multiplex bag making machine, the shoes appearing in vertical cross section;

Fig. 2 is a vertical section taken on a plane corresponding to line 2-2 of Fig. 1;

Fig. 3 is a plan view of Fig. 1, part of the cutting mechanism being removed to more clearly illustrate the invention;

Fig. 4 is a perspective view of my invention detached from the cutting unit of the bag machine;

Fig. 5 is a fragmentary sectional view, partly in elevation, showing the manner in which the liner and cover are drawn past the shoes;

Fig. 6 is a perspective view of the relative position of the cover and liner when the cover is passing under the shoe, a portion of the liner being broken away to clearly illustrate the manner in which the two webs of paper, of different thicknesses, are cut at the same time;

Fig. 7 is a bottom view of one of the shoes;

Fig. 8 is a plan view of the cover with the liner placed thereupon to show the respective difference in width of said liner, as compared with said cover; and

Fig. 9 is a perspective view of a portion of the bag machine, parts being broken away and omitted and showing the invention installed thereon.

In the embodiment of my invention as illustrated and which shows a preferred construction I provide a single cutting unit which comprises side frames 1, shafts 2 and 3 and dieing out cylinders 4, 4a and 4b and cooperating dieing out cylinders 5, 5a and 5b, respectively. Shafts 2 and 3 are rotatably mounted in the side frames 1 and are adapted to be driven in opposite directions in the usual and well-known manner. Shoes 6 and 7 are horizontally disposed between shafts 2 and 3, respectively, and shoe 6 is positioned between dieing out cylinders 4 and 4a and dieing out cylinders 5 and 5a. Shoe 7 is horizontally disposed between shafts 2 and 3 and positioned between dieing out cylinders 4a and 4b and 5a and 5b, as clearly shown in Figs. 1 and 3. The shoes 6 and 7 are suitably attached to horizontal bars 8 and 9 by screws 10, as clearly shown in Figs. 2, 3, 4 and 9. Said bars 8 and 9 are supported by side frames 1 through stud bolts 10a, plates 11 and nuts 12. The plates 11 are securely fixed to the top 13 of side frames 1 by bolts 14, as clearly shown in Figs. 1, 2, 3 and 9, respectively. The inner edges 8a and 9a of bars 8 and 9 are tapered or beveled to permit the edges of the two webs of paper to be firmly held between the dieing out cylinders 4, 4a and 4b and 5, 5a and 5b, respectively, as shown in Figs. 2 and 9.

Should it be desired to raise or lower the shoes 6 and 7 such adjustment can be accomplished through the adjustment of nuts 12. If a lateral adjustment of said shoes is desired, this can be accomplished by loosening screws 14 until said adjustment is made and then tightening said screws to hold said adjustment.

Dieing out cylinders 4, 4a and 4b are fixed upon shaft 2 by set screws 18 while cylinders 5, 5a and 5b are fixed upon shaft 3 by set screws 19.

The operation of my invention is as follows:

As shown in Fig. 8, it will be noticed that the liner 15 is of a greater width than cover 16 on one side and that cover 16 is of a greater width than liner 15 on the other side after dieing out. In order to simultaneously cut the liner 15 and cover 16 with one cutting unit it is necessary to pass the liner 15 over the horizontally disposed bars 8 and 9 and the cover 16 beneath the shoes 6 and 7, as clearly shown in Figs. 5 and 9. With an arrangement of this nature, it will be clearly apparent that the difference in width of the cover relative to the liner is taken care of by passing beneath the shoes 6 and 7. When the liner and cover pass beyond the shoes 6 and 7 the cover 16 is again flattened out, as shown in Fig. 9, thus maintaining the liner in proper registry with the cover for the subsequent operations upon the bag blank.

If desired, the shoes 6 and 7 may each be

provided with an elongated groove 17 on its under side, which groove assists to maintain proper registry of the cover relative to the liner while passing the edges of said cover and liner between the dieing out cylinders. 70

Some of the present advantages of this invention are that the liner and cover are cut to different widths simultaneously and with but a single cutting unit; more perfect registry of the liner upon the cover is 75 maintained; and the scoring operation is adapted to precede the printing operation.

Another advantage of this invention is that I eliminate one cutting unit; also one exhaust hopper and piping system for same, as well as a blower which, needless to say, eliminates 80 attention and adjustment and cuts down the lost time in operation of the machine.

Having thus described my invention, what I claim as new and desire to secure by Letters 85 Patent is:

1. In a paper bag machine having means for feeding two webs of superimposed paper of different widths, in combination with a single cutting unit for simultaneously cutting the webs to form bag blanks, and means associated with said cutting unit to compensate for the difference in width of said superimposed plies of paper, comprising a pair of horizontally disposed shoes located centrally of said cutting unit and between said webs. 90

2. In a paper bag machine having means for feeding two webs of superimposed paper of different widths, in combination with a single cutting unit adapted to receive and cut both webs of paper to form bag blanks, comprising one set of dieing out rollers, spacing means between said rollers over which one web of the paper is adapted to be passed and under which the remaining web of paper is adapted to be passed, said spacing members compensating for the difference in width of 100 said webs of paper. 105

3. In a paper bag machine having means for feeding two webs of superposed paper of different widths, in combination with a single cutting unit adapted to receive and cut both webs of paper to form bag blanks, comprising a single set of dieing out rollers, 115 spacing shoes located between said rollers, the undersides of which are tapered upwardly, and means for adjustably supporting said shoes, said shoes compensating for the difference in width of said lower web of paper 120 relative to said upper web of paper. 120

4. In a paper bag machine having means for feeding two webs of superposed paper of different widths, in combination with a single cutting unit adapted to receive and cut both webs of paper to form bag blanks, comprising a single set of dieing out rollers, spacing shoes located between said rollers, and means for adjustably supporting said shoes, said shoes compensating for the difference in 130

width of said lower web of paper relative to said upper web of paper.

5. A paper bag machine, as specified in claim 3, wherein the means for adjustably supporting said shoes comprises a pair of horizontally disposed spaced apart bars, stud bolts attached to said bars, a plurality of plates supported by said bag machine, and nuts threaded to the upper ends of said stud bolts whereby said bars may be raised or lowered, thereby raising or lowering said shoes relative to said dieing out rollers.

6. In a paper bag machine having means for feeding two webs of superimposed paper of different widths, in combination with a single cutting unit adapted to receive and cut both webs of paper simultaneously to form bag blanks and comprising a single set of dieing out rollers, tapering spacing shoes located between said rollers and parallel to each other over which shoes one web of paper is adapted to be passed and under which the remaining web of paper is adapted to be passed, said shoes compensating for the difference in width of said webs of paper, and an elongated groove extending lengthwise in the bottom of each shoe adapted to receive the central portion of the bottom web, whereby said bottom web is adapted to be held in perfect registry with the top web.

7. In a paper bag machine having means for feeding a plurality of superimposed webs of paper of different widths through the machine, a single set of cutting rollers adapted to receive and simultaneously cut both webs to form bag blanks, a pair of horizontally disposed shoes associated with said cutting rollers whereby when the lower web of paper is passed beneath said shoes its difference in width relative to the web of paper passed above said shoes is compensated for at the time said plurality of webs of paper are passing between said single set of cutting rollers.
